CLAIM

The ornamental design for an automatic wake-up light, as shown and described.

DESCRIPTION

FIG. 1 is a perspective view of an automatic wake-up light showing my design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view thereof in a usage state;

FIG. 10 is an enlarged view of area **10** circumscribed in FIG. 2; and,

FIG. 11 is an enlarged view of area **11** circumscribed in FIG. 4.

The broken lines consisting of evenly spaced short dash lines in the drawings depict portions of the automatic wake-up light that form no part of the claimed design.

The broken lines consisting of long and short dash lines in the drawings depict the boundaries of the enlarged views and form no part of the claimed design.
